BOTTLE

Paul G. Kemp, London, Ontario, Canada

Filed Oct. 21, 1965, Ser. No. 87,707

Term of patent 14 years

(Cl. D58—8)

The figure is an elevational view of a bottle showing my new design, with a portion broken-away to indicate indeterminate length.

The bottle is circular in all cross-sections and the finish has a conventional circular opening therethrough.

I claim:

The ornamental design for a bottle, as shown and described.
